UNITED STATES PATENT OFFICE.

SAMUEL I. ROSE, OF CLEVELAND, OHIO, ASSIGNOR TO THE OSBORN-CREW MANUFACTURING COMPANY, OF CLEVELAND, OHIO, A CORPORATION OF OHIO.

DESIGN FOR A TOY WAGON.

59,872.

Specification for Design.

Patented Nov. 29, 1921.

Application filed August 3, 1921. Serial No. 489,641. Term of patent 7 years.

To all whom it may concern:

Be it known that I, SAMUEL I. ROSE, a citizen of the United States, residing at Cleveland, in the county of Cuyahoga and State of Ohio, have invented a new, original, and ornamental Design for a Toy Wagon, of which the following is a specification, reference being had to the accompanying drawing, forming a part thereof.

In said drawing, Figure 1 is a side elevation and Fig. 2 is an end elevation.

I claim:

The design for toy wagon substantially as shown.

SAMUEL I. ROSE.
